C. H. BROWN

UNDERREAMER

Filed May 28, 1928

Patented Feb. 14, 1928.

1,659,514

UNITED STATES PATENT OFFICE.

CHARLES H. BROWN, OF BRECKENRIDGE, TEXAS.

UNDERREAMER.

Application filed May 28, 1926. Serial No. 112,350.

This invention relates to an improvement in underreamers, and has for its object to provide a device of this character wherein a plurality of reamer blades are provided and are so constructed and organized with the body of the reamer that they are firmly and rigidly supported in operative position with their shanks protected against wear. This feature greatly facilitates the dressing 10 of the blades, since it makes it practical to use a dressing form with the blades when re-shaping or renewing their cutting edges.

Another object of the invention resides in the provision of an adjustable carrier for 15 the reamer blades which may be adjusted to take up wear that occurs.

A further object is to provide a novel means for expanding the reamer blades and in conjunction with this means a novel 20 means for releasing the expanding means, the releasing means operating in conjunction with the casing of the well and in such manner as to relieve the cutting blades and their mounting or carrier of strains and 25 stresses which would be liable to result in loss of the blades.

A further object is to provide a novel reamer blade structure.

A still further object resides in the provision 30 of an underreamer which may be used to straighten crooked holes.

Other objects and advantages reside in certain novel features of the construction, arrangement and combination of parts which 35 will be hereinafter more fully described and particularly pointed out in the appended claims, reference being had to the accompanying drawings forming a part of this specification, and in which:

40 Figure 1 is a view in elevation showing an underreamer constructed in accordance with the present invention.

Figure 2 is a view in section on the line 2-2 of Figure 1, parts being shown in elevation for the sake of illustration.

45 Figures 3, 4 and 5 are views in horizontal section on the lines 3-3, 4-4 and 5-5, respectively, of Figure 2.

Figure 6 is a bottom plan view of the un- 50 derreamer.

Figure 7 is a detail perspective view of one of the adjusting pins for adjustably supporting the blade carrier on the body of the underreamer.

55 Figure 8 is a view thereof in transverse section.

Referring to the drawings, it will be seen that the underreamer embodying the present invention includes a cylindrical body 1 formed with a longitudinally extending bore 60 or opening 2 which leads to a point adjacent the upper end of the body down through the lower end thereof.

A plurality of reamer blades designated generally at 3 are provided, and are mounted on the lower end of the body by means of an adjustable carrier 4. Preferably three reamer blades 3 are provided, and these blades are of identical construction. Each includes a body portion 4^a having an upwardly extending shank 5 and a downwardly and outwardly extending cutting portion 6. At the juncture of the shank 5 and the body portion 4^a, a shoulder 7 is provided, as the shank 5 is offset inwardly from 70 the outer periphery of the body portion 4^a. As shown in Figure 6 of the drawing, the corners of the cutters are rounded as shown at 3^a, the advantage of this rounded formation of the corners residing in the fact that 75 such corners will not burn off in the forge, are less liable to check when hardened, and are more easily dressed. The inner periphery of the shank 5 and the body portion 4^a of each blade are continuous and merge into 80 each other, and together constitute a curved and inclined camming wall 8 which is spaced inwardly and upwardly from the cutting portion 6 of the blade. Adjacent its upper end each shank 5 is provided with a slot 9 85 which opens out through its inner face. In the assembly, the slots 9 of the blades 3 receive an outwardly directed annular flange 10 provided on the lower end of the cylinder body 11 of the adjustable carrier 4. The 90 flange 10 is loosely fitted in the slots 9 to permit the reamer blades to partake of their operative movements and yet to hold them against displacement from the body and against longitudinal movement with respect 95 thereto. The body portion 11 of the carrier 4 also has a pair of spaced annular flanges designated at 12 and 13 and located above the flange 10. The flanges 12 and 13 receive between them a pair of supporting pins 100 designated generally at 14. The section of the body portion 11 located between the pair of flanges 12 and 13 has a pair of faces 11^a, the members of the pair of faces 11^a being opposite, and also has a pair of faces 11^b, the members of the pair of faces 11^b being 105 opposite each other, the faces 11^b being

110

spaced angularly 60° from the faces 11^a. In the drawing, the pins are shown cooperating with the faces 11^b, but by shifting the carrier in the casing the faces 11^a may be brought into coaction with the pins, thereby distributing the wear in that in reassembling the blades with the reamer, their positions may be positively changed and the bottom of the body 1 may be worn evenly.

10 Each pin 14 has rounded ends designated at 15 and 16 and engage bearings 17 and 18 respectively provided on the body portion 1 of the underreamer as shown to advantage in Figure 4. Intermediate the journals 15 and 16 each pin 14 has a plurality of flat faces designated at 19, 20 and 21, the faces 19, 20 and 21 being eccentric with respect to the pin and being located at different radial distances from the center or axis of rotation of the pin. The ends 15 of the pins are provided with openings to coact with screws or other fastening means for holding the pins in any adjustment for preventing accidental displacement thereof. It is obvious that 25 when the surface 19 is engaged with the flange 12 of the body portion 11 of the carrier 4, the carrier will be adjustably secured in one position on the body portion 1 of the reamer, whereas when the surfaces 20 and 21 are brought into engagement with the carrier, this carrier will be supported in other positions, and this provides the adjustment necessary to take up wear.

The carriers 4 are preferably provided in sets, each set for each tool consisting of four carriers. The carriers of each set are of similar construction but differ in the spacing of the flanges 10 and 13, the body portion 11 of the carriers of the set being successively shorter. With such a set of carriers after the pins 14 have been adjusted to take up the maximum amount of wear that they can handle, which is usually one-fourth of an inch, then a shorter carrier 4 is put into the 40 tool and another one-fourth inch of wear may be taken up. This process is repeated until all the sets of carriers have been used.

Expanding means is provided for the reamer blades, and comprises a mandrel 25 extending axially through the opening of the body 1 and having a frusto-conical expanding member 26 welded or otherwise suitably secured to enlargements 27 and 28 provided on the mandrel. The periphery of this 55 frusto-conical expanding member 26 is adapted to engage the curved and correspondingly formed walls 8 of the reamer blades. Spring means is provided for urging the mandrel 25 to such position that its 60 expanding member 26 engages the reamer blades and expands the same, and this spring means preferably consists of a compression coil spring 29, the lower end of which rests on the carrier 4, and the upper end of which 65 engages an adjustable abutment on the man-

drel which is preferably in the form of a nut 30 threadedly engaged with the mandrel and held in position by a lock nut 31.

When the reamer blades are expanded by the expanding member 26, the outer peripheries of their shanks 5 snugly engage the inner wall of the body portion 1, as illustrated in Figure 5, and the shoulders 7 of the blades abut against the lower end of the body of the underreamer. In this way the reamer 75 blades are rigidly and securely held in position and very little if any wear can occur except on the cutting edges.

Releasing means is provided for the expanding means and consists of a pair of riders or shoes 35 fixed on the lower ends of arms 36 having their upper portions in-turned and pivotally connected, as at 37, to a supporting and connecting member 38 which has its lower end flanged and recessed, as at 38^a and fitting over the upper rounded end 40 of the mandrel 25. The supporting member 38 is held engaged with the mandrel by means of a light coil spring 41.

The shoes 35 have rearwardly directed flanges 42 inset from their edges and terminating in angularly offset lips 43 which coact with the body 1 of the reamer to limit displacement of the shoes in their operative position.

As shown in Figures 1, 2 and 3, the shoes 35 operate in slots 44 provided in the body 1 and extending from the internal opening of the body out through the periphery thereof.

At their lower ends the slots 44 have enlargements 45. With this arrangement when the shoes operate in the slots 44 they are held against any substantial degree of transverse displacement by virtue of the engagement of the edges 42 of the shoes with the outer marginal walls of the slots 44 and the engagement of the flanges 43 with the inner marginal walls of said slots. The outward displacement of the shoes is always limited by the action of the flanges 43 which have sufficient extent to engage the inner marginal walls of the enlargements 45 as well as the inner marginal walls of the slots 44. The enlargements 45 are of sufficient size, however, to accommodate the shoes 35 when the shoes 35 are positioned in opposed relation with the enlargements. With this arrangement when the underreamer is pulled up to the casing shoe, the shoes 35 engage the casing shoe and are held stationary while the body of the mandrel continues to move upwardly. This results in a compression of the spring 29 and the lowering of the expanding mandrel, permitting the cutters to move to an inoperative position out of the way of the casing shoe. This action continues until the shoes 35 come into alignment with the enlargements 45 whereupon the shoes 35 move into the body of the underreamer and in so doing are disengaged from 130

the casing shoe and consequently move upwardly with the body of the underreamer. The assembly of the shoes is brought about by inserting the shoes or riders with their 5 arms up through the lower end of the body and passing the shoes outwardly through the enlargements 45 of the slots 44.

The body 1 of the underreamer has a tool joint 46 at its upper end, and below the tool 10 joint the body 1 is provided with a tapered and externally threaded portion 47 designed to receive a pipe or string of tubing 48 which co-acts with the well casing and serves as a guide when the underreamer is used to 15 straighten crooked holes.

I claim:—

1. An underreamer including a body having an opening therein extending out through the lower end thereof, reamer blades 20 having shanks extending up into the lower end of the body and having cutting portions projecting below the body, means cooperable with the shanks of the blades for mounting the blades on the body, including a carrier 25 having means interengageable with the shanks of the blades, and supporting pins adjustably mounted on the body and engageable with the carrier for supporting the same in any one of a plurality of 30 adjustments, and means for expanding the blades.

2. An underreamer including a body having an opening therein extending out through the lower end thereof, reamer blades 35 having shanks extending up into the lower end of the body and having cutting portions projecting below the body, means cooperable with the shanks of the blades for mounting the blades on the body, including a carrier 40 having means interengageable with the shanks of the blades, and supporting pins having portions rotatably mounted on the body and having flat faces located at different distances from the centers of the pins 45 and selectively engageable with the carrier for supporting the same in a plurality of adjusted positions, and means for expanding the blades.

3. An underreamer comprising a body, a 50 plurality of reamer blades, means for mounting the reamer blades on the end of the body for operative movement in cutting walls of the bore, means for expanding the reamer blades including a mandrel, and an 55 expanding member fixed on the mandrel and cooperative with the reamer blades, spring means for urging the mandrel to such position as to cause the expanding member to expand the blades, and means for releasing the expanding means and including a pair 60 of shoes, said body having slots through

which the shoes project, said shoes having flanges engageable with the edges of the slots to limit the movement of the shoes in certain phases of the operation, said slots 65 having enlarged portions to permit the shoes to move into the body in other phases of the operation.

4. An underreamer comprising a body, a plurality of reamer blades, means for 70 mounting the reamer blades on the end of the body for operative movement, means for expanding the reamer blades including a mandrel, and an expanding member fixed on the mandrel and cooperative with the 75 reamer blades, spring means for urging the mandrel to such position as to cause the expanding member to expand the blade, and means for releasing the expanding means and including a pair of shoes, said body 80 having slots through which the shoes project, arms carrying the shoes, and a combined connecting and supporting member pivoted to the arms and engaging the mandrel, and a spring for maintaining the combined connecting and supporting member engaged with the mandrel.

5. An underreamer including a body having an opening therein extending out through the lower end thereof, reamer 90 blades having shanks extending up into the lower end of the body and having cutting portions projecting below the body, means cooperable with the shanks of the blades for mounting the blades on the body, including a carrier having means interengageable with the shanks of the blades, and supporting pins adjustably mounted on the body and engageable with the carrier for supporting the same in any one of a plurality 95 of adjustments, said carrier having angular spaced pairs of lateral faces selectively engageable with said pins, and means for expanding the blades.

6. An underreamer including a body having an opening therein extending out through the lower end thereof, reamer blades having shanks extending up into the lower end of the body and having cutting portions projecting below the body, means cooperable with the shanks of the blades for mounting the blades on the body, including a carrier having means interengageable with the shanks of the blades, and means adjustably mounted on the body and engageable with the carrier for supporting said carrier in any one of a plurality of adjustments, said carrier having angular spaced pairs of lateral faces selectively engageable with said means, and means for expanding 100 the blades.

CHARLES H. BROWN.
